UNITED STATES PATENT OFFICE.

ROBERT S. MENNIE, OF CHICAGO, ILLINOIS, ASSIGNOR TO FLANNERY BOLT COMPANY,
OF PITTSBURGH, PENNSYLVANIA.

STAYBOLT STRUCTURE.

1,354,620.

Specification of Letters Patent.

Patented Oct. 5, 1920.

Original application filed February 5, 1916, Serial No. 76,333. Divided and this application filed August 29, 1919. Serial No. 320,647.

To all whom it may concern:

Be it known that I, ROBERT S. MENNIE, a citizen of Canada, and a resident of Chicago, in the county of Cook and State of Illinois, have invented certain new and useful Improvements in Staybolt Structures; and I do hereby declare the following to be a full, clear, and exact description of the invention, such as will enable others skilled in the art 10 to which it appertains to make and use the same.

This invention relates to improvements in staybolt structure for boilers,—this application being a division of application for patent filed by me on the 5th day of February 1916 and designated by Serial No. 76,333.

The object of my present invention is to provide a staybolt structure embodying a bearing sleeve of the "flush" type in which both the outer end of the bearing sleeve and its closure shall be located inwardly from the plane of the outer face of the boiler sheet whereby the outer face of the closure will be 25 in the same plane as the outer face of the boiler sheet, and to so mount the sleeve and its closure that the same will effectually withstand all strains and pressure to which they may be subjected.

With this and other objects in view, the invention consists in certain novel features of construction and combinations of parts as hereinafter set forth and pointed out in the claims.

The accompanying drawing is a sectional view showing an embodiment of my invention.

1 represents an outer boiler sheet having an opening 2, which latter is counterbored, 40 as at 3, in such manner as to provide an annular seat 4 located near the inner face of the sheet. Thus it will be seen that the inner portion of the opening 2 is appreciably less in diameter than is the diameter of the remaining portion of said opening.

A bearing sleeve 5 is passed through the opening 2 and is of sufficient length to project some distance beyond the inner face of the boiler sheet. The outer end of the sleeve 50 4 is provided with an annular, outwardly projecting flange or shoulder 6 disposed within the larger portion 3 of the opening 2 and rests against the annular shoulder 4.

The sleeve 5 is made with an interior

curved or rounded face 7 which constitutes 55 a seat for the rounded head 8 at the outer end of a stay bolt 9, the inner end of which latter will be secured to the inner boiler sheet as will be readily understood.

It will be observed that the outer end of 60 the sleeve is mounted freely within the boiler sheet, between the inner and outer faces thereof and that the mounting is such as to effectually withstand any inward pull which may be exerted by the staybolt.

The outer end of the bearing sleeve 5 is 65 closed by a plate or closure 10 which rests against the outer end of said sleeve and the seat within the latter for the bolt head is so located that a clearance 11 will be provided 70 between said bolt head and closure to accommodate the longitudinal play of the staybolt.

The plate or closure 10 may be of such 75 thickness that when in position against the sleeve and within the outer portion of the opening, its outer face will be substantially flush with the outer face of the boiler sheet. The peripheral portion of the plate or closure is beveled, as at 10^a, thereby forming 80 (with the wall of the opening 2) a groove which is occupied by a welding alloy 12, and thus the plate or closure is integrally united by welding to the boiler sheet within the opening 2 and over the outer end of the 85 bearing sleeve.

For the purpose of providing for the testing of the staybolt, the latter may be provided with a tell-tale hole 13 closed at 14 within the head 8 of the staybolt, and 90 this tell-tale hole may extend to the inner end of the staybolt.

Having fully described by invention what I claim as new and desire to secure by Letters-Patent, is:—

95

1. In a staybolt structure, the combination with a boiler sheet having an opening, of a bearing sleeve having its outer end seated within said opening, a staybolt having a head mounted in said sleeve, and a 100 closure in said opening over the sleeve and secured to the boiler sheet.

2. In a staybolt structure, the combination with a boiler sheet having an opening, of a bearing sleeve having its outer end seated within said opening, a staybolt having a head mounted in said sleeve, a closure in said opening in the boiler sheet,

and a weld uniting said closure to the boiler sheet.

3. In a staybolt structure, the combination with a boiler sheet having an opening, 5 of a bearing sleeve having its outer end seated within said opening, a staybolt having a head mounted in said sleeve, a closure located within said opening in the boiler sheet with its outer face approxi- 10 mately flush with the outer face of the boiler sheet, and a weld uniting the peripheral portion of said closure to the boiler sheet.

4. In a staybolt structure, the combination 15 with a boiler sheet provided with an opening, and an annular seat within said opening between the respective faces of the sheet, of a bearing sleeve having an annular shoulder at its outer end inclosed within the 20 opening in the boiler sheet and resting against the annular seat therein, and a closure in said sleeve and secured to the boiler sheet.

5. In a staybolt structure, the combination 25 with a boiler sheet provided with an

opening, the wall of which is formed with an annular shoulder, of a bearing sleeve having an annular shoulder resting against the annular shoulder in said opening, a staybolt having a head mounted in said bearing 30 sleeve, and a closure for the outer end of said sleeve, said closure secured to the boiler sheet.

6. In a staybolt structure, the combination 35 with a boiler sheet provided with an opening, the wall of which is formed with an annular shoulder, of a bearing sleeve having an annular shoulder at its outer end seated on the annular shoulder in said opening, a staybolt having a head mounted in 40 said bearing sleeve, and a closure located over the bearing sleeve within the opening in the boiler sheet and welded to the latter.

In testimony whereof, I have signed this specification in the presence of two sub- 45 scribing witnesses.

ROBERT S. MENNIE.

Witnesses:

HARRY GRONERT,
JAS. FLETCHER.
